UNITED STATES PATENT OFFICE

WILLIAM A. WITHERS, OF CHICAGO, ILLINOIS, ASSIGNOR TO AIRUBBER CORPORATION,
OF CHICAGO, ILLINOIS, A CORPORATION OF ILLINOIS

COMPOSITE MATTRESS

Application filed November 10, 1926. Serial No. 147,416.

The invention relates to improvements in composite mattresses and has particular reference to mattresses of the type in which the resiliency of the same is mainly secured by the use of fluid filled cells or compartments. 5 In mattresses of the particular type described, difficulty has been experienced by reason of the fact that a flexible envelope when charged with fluid such as air tends to expand into the form of a sphere. In the case of 10 pneumatic mattresses, such tendency has been corrected by the use of ties of various kinds extending from top to bottom of the mattress, or recourse has been had to a structure made with a plurality of compartments therein. 15 However, even with the best types of construction, the outside of such a pneumatic mattress obviously takes the cross sectional form of a semicircle. Although the semi- 20 circle shape of the edge of the mattress is not of serious import where the mattress is to be used for camping or other temporary purposes, serious objection has been made to this rounded appearance where the mattress is to 25 be used for general use on bedsteads in the home.

Also, in view of the fact that one of the principal virtues of a pneumatic mattress is its capacity to support its load at an even 30 pressure, (in pounds per square inch wherever contact is established,) it is desirable that all of the cells or compartments of the mattress should communicate with each other so that the pressure may be uniform throughout the 35 entire area of the supporting surface. Or, at any rate, for this reason the number of compartments should be kept at a minimum. Under this condition, the mattress is highly efficient as a piece of sleeping equipment, but 40 if one attempts to sit upon the same or upon the edge of the same the fluid, because of the weight being concentrated upon a small area of the mattress, will merely distend more completely the remoter portions of the mattress before the internal fluid pressure has 45 reached the amount necessary to support the load, thus permitting the upper and lower surface of the loaded portion to come together and the resiliency of the mattress being there- 50 by completely or partially lost.

Hence, it will be readily understood that the principal objects of the present invention are to provide a mattress of the pneumatic or fluid content type having a shape and appearance, particularly with respect to its side edges, substantially equal to the standard for an ordinary mattress of general use; to provide a mattress of the said type which is free from the discomfort ordinarily experienced when sitting upon the usual type of pneumatic mattress; to provide a construction which may be conveniently and economically manufactured and which shall be relatively simple to install and manipulate, while being rugged, durable, and efficient in use, and in general, to provide an improved composite mattress of the character referred to. 55 60 65

In the drawings which accompany this application and in which the invention is illustrated as applied to a mattress of full size,

Fig. 1 is a plan view of the complete mattress. 70

Fig. 2 is a section taken on the line 2—2 of Fig. 1.

Fig. 3 is a section taken on the line 3—3 of Fig. 1, and 75

Fig. 4 is a perspective view of the tick portions and associated casings prior to the insertion of the inner pneumatic filling.

Referring to the drawings, 10 represents the pneumatic filling which, in the present instance, comprises a pneumatic mattress construction of a type now widely and favorably known in the trade. With this type of mattress there is an upper sheet 11 and a lower sheet 12 of suitable fabric, the interior face of which is lined or coated with a rubber compound. These sheets are joined together at their outer edges 13 and 13 so as to seal the interior as a whole and also between the 80 sides of the pneumatic unit, the sheets 11 and 12 are united together at intermediate points, for example, 15, to prevent the improper bulging of the unit and thereby maintain it in generally flat condition. In the present instance the connections 15 take the form of a series of parallel lines as shown best at 16 in Figs. 1 and 2. 85 90 95

In order to enable the pneumatic unit to be inflated from a single valve element 17, and 100

also to enable the fluid contents to be distributed throughout the area of the unit, the junction lines 16 do not extend quite to the border junctions 13 and 14, but stop slightly short thereof as shown at 18 and 19 in Fig. 2.

The pneumatic unit before inflation is introduced into a casing constructed as follows. The elements of the casing include an upper tick portion 20 and a lower tick portion 21 which extend over the entire area, top and bottom respectively, of the pneumatic unit. Each tick part serves as a tie or connection for the border which extends around the pneumatic unit and said border element also serves 15 as a connector between the adjacent edges of said tick parts.

The said border as to each side or end of the mattress comprises stuffed hollow casings which are made with duplex parts 22 and 23. Each of said duplex parts 22 or 23 is composed of an outer extension 24 of the main tick part 20 or 21 to which, at points 25 and 26 there is sewed an auxiliary casing element 27 of the necessary dimensions, so that when the upper auxiliary casing element 27 is united to the lower auxiliary casing element 28 by stitch lines 29 and 30, the pressure of the outer cell 31 of the pneumatic unit will fill the concavity in the border casing as a whole and the outer face between stitch lines 25, 30, and 32, will be in a substantially straight line. In order still further to improve the appearance of the mattress, a line of roll edge stitching 33 may 35 be employed.

The stuffing material preferably consists of a good grade of mattress filling, for example, curled hair or cotton felt. It will be observed also that with the duplex construction of the border casing that those portions 34 of the elements 27 and 28 which extend between the stitch lines 29 and 30, serve to tie in the edge of the mattress between its corners thereby to produce and maintain a neat vertical 45 wall effect.

Two sides and the foot end 35 of the border casing are treated in the same manner as indicated in Fig. 3 of the drawings. The head end of the border casing as shown in Fig. 4 50 of the drawings, is initially left open in order to permit insertion of the pneumatic unit before the latter is inflated. After the deflated pneumatic unit is inserted through the opening 36, the operator sews up the duplex plates 37 and 38 which have been previously formed by lines of hemstitching 39 and 40, the final stitching being represented by the numeral 41. Since the mattress before inflation is 55 much less bulky than subsequent thereto, it may be inserted in the casing through an opening which is considerably less than the full width of the mattress, as well shown in Fig. 4. After the stitch line 41 is finally completed, the mattress may be inflated 60 through the valve 17.

It will be observed that if desired the inflation of the mattress may be postponed until the mattress is in the hands of the dealer purchaser, it being understood that, in common with mattresses of the pneumatic type, only sufficient air should be introduced to provide the necessary support. Care should be taken that the mattress is not inflated too hard, otherwise the pressure developed by load will be too great with the result that the lack of 70 supporting area may cause discomfort.

The described details of construction are illustrative of a single application only of the invention, the scope of which should be determined by the appended claims which, it is desired, should be construed as broadly as possible consistent with the state of the art.

I claim as my invention:

1. In a composite mattress, the combination of a main body portion comprising a plurality of connected flexible cells containing charges of fluid distending said cells to substantially the desired thickness of the mattress as a whole, upper and lower ticks between which said fluid filled part is interposed, and border portions disposed adjacent the edges of said main body portion and connected together by said ticks so as to be maintained in place adjacent said edges, said border portion comprising casings filled with resilient non-fluid material and having their inner faces shaped to fit the outer surfaces of the fluid filled portion and their outer faces shaped to provide substantially square edges for the mattress.

2. In a composite mattress, the combination of a main inner portion comprising a pair of impervious sheets united together at their edges and at intermediate points in their area, the space between the sheets being filled with fluid so as to distend the sheets to form cells, the outer edge portions of said inner portion being substantially hemispherical in cross section and the thickness of said inner portion being substantially equal to the desired thickness for the mattress as a whole, tick parts extending above and below the said inner fluid filled portion, and side casings connected together by said upper and lower tick parts and also connecting together the adjacent edges of the upper and lower tick parts, said casings having their inner faces of concave shape to fit the outer surfaces of the fluid filled mattress portion and being filled with resilient non-fluid material.

3. In a composite mattress, the combination of a main body portion composed of a plurality of communicating cells having a charge of fluid for distending the cells, a tick comprising top and bottom tick members between which said main body is interposed, and a border providing a substantially square edge appearance for the body, said border including marginal portions of said top and bottom tick members, and fabric strips se-

cured to each of said tick members adjacent its edge and at a point spaced inwardly from said edge so as to form top and bottom tubular casings adjacent the edges of the respective tick members, a filler of resilient, non-fluid material in said casings, and means uniting said casings together intermediate said ticks.

4. In a composite mattress, the combination of a main body portion composed of a plurality of communicating cells having a charge of fluid for distending the cells, a tick comprising top and bottom tick members between which said main body is interposed, and a border providing a substantially square edge appearance for the body, said border including marginal portions of said top and bottom tick members, and fabric strips secured to each of said tick members adjacent its edge and at a point spaced inwardly from said edge so as to form top and bottom tubular casings adjacent the edges of the respective tick members, a filler of resilient, non-fluid material in said casings, and means formed integral with the top and bottom casing members for facilitating uniting or separation of a portion thereof, thereby facilitating insertion or removal of the main body into or from the tick.

0 WILLIAM A. WITHERS.

CERTIFICATE OF CORRECTION.

Patent No. 1,730,752.

Granted October 8, 1929, to

WILLIAM A. WITHERS.

It is hereby certified that the above numbered patent was erroneously issued to "Airubber Corporation, of Chicago, Illinois, a Corporation of Illinois", whereas said patent should have been issued to "New York Rubber Corporation, of New York, N. Y., a Corporation of New York", said corporation being assignee by mesne assignments of the entire interest in said invention, as shown by the records of assignments in this office; and that the said Letters Patent should be read with this correction therein that the same may conform to the record of the case in the Patent Office.
